UNITED STATES PATENT OFFICE.

BAILEY G. BIRD AND HENRY D. WRIGHT, OF MCCOMAS, WEST VIRGINIA.

ELECTRIC POWER REEL.

Application filed February 12, 1925. Serial No. 8,736.

The present invention relates to an electric power reel designed for advanced mining machinery such as coal loaders, coal cutters, and drilling machinery, that is mining machines which operate in advance of the stationary supply trolley system. The reel is supplied with current passing over a flexible cable, one end of which is attached to the trolley wire and the other end attached to the reel, the reel being directly coupled to the machine.

The principal object of the invention is to provide a reel of this nature possessed of simplicity of construction, few parts which are readily accessible, and one which is thoroughly reliable and efficient in operation.

A still further important object of the invention is to provide a reel of this nature which is strong, durable, inexpensive to construct, not liable to readily get out of order, and otherwise well adapted to the purposes for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is an elevation of the reel embodying the features of our invention showing a portion thereof in section,

Fig. 2 is a transverse section taken there-through substantially on the line 2-2 of Fig. 1,

Fig. 3 is an end elevation of the reel,

Fig. 4 is a transverse section through the reel taken on the line 4-4 of Fig. 1,

Fig. 5 is a top plan view of the brush holder,

Fig. 6 is an end elevation thereof, and

Fig. 7 is a side elevation thereof.

Referring to the drawing in detail, it will be seen that two housings 5 are provided on their outer surfaces with journals 6 having oil cups 7 extending therein. A shaft 8 is journaled through the housings and is prevented from longitudinal movement by the collars 9 held in place by set screws 10. The reel proper indicated generally by the letter R is mounted on the shaft

8 between the housings 5. This reel R includes the wooden disks 12 which support the annular series of rods 13 therebetween.

Collars 14 receive the shaft 8 and are fixed thereto by set screws 15. Flanges 16 are provided on these collars 14 and are fixed to the disks 12 by the bolts 17 so that the reel will rotate with the shaft 8. The shaft may be actuated in any suitable manner and one end thereof is squared as at 18 in order that a crank may be engaged thereon for manually turning the reel.

The numeral 19 designates the flexible cable adapted to be wound about the reel and in the present instance there are two of these cables, the ends of which terminate adjacent the disks 12 and are connected to bolts 20 extending through the disks and through the flanges 21 of the collector ring 22. This collector ring 22 is held in place on the outer surfaces of the disks 12 within the housings 5 by the bolts 20 and screws 23. A brush holder H is supported in each of the housings 5 for holding its brush in engagement with the collector ring 22. The cable 25 passes through an opening in this housing and is connected with the holder H and is supported by a clamp 26 provided on the side of the housings.

The construction of the brush holder may be better understood by reference to the Figs. 5, 6 and 7 of the drawing. The body of the brush holder is indicated by the numeral 28 and has a square opening 29 in one end thereof for receiving the brush 30 which may be of any conventional type. A recess 31 is provided at the other end of the body adjacent one edge thereof and a bolt or pin 32 extends transversely therethrough and is held against displacement by a cotter pin 33. A series of teeth or projections 3 are provided on one side of the body 28 at its recessed end for receiving therebetween a rod 34 which is extended from the head of the bolt or pin 32. A curved spring 35 is fixed to the bolt and extends out of the recess to engage an end of the brush 30 and hold it against the collector ring.

By adjustment of the bolt 32 by means of rod 34 this spring 35 may be tensioned as desired. The bolt 36 forms a means for attaching the wire 25 to the brush holder. The bolt 37 passes through the brush holder

being insulated therefrom as at 38. This bolt 37 also passes through the sides of the respective housings as is shown in Fig. 1.

The current between the wires 19 and 25 5 may now easily be followed through the bolt 20, flange 21, electric collector 22, brush 30, brush holder H, bolt 36.

It will be apparent that the device 10 possesses extreme simplicity and few parts, all of which are accessible. The shaft may be properly lubricated and the oil will not engage with the electric parts.

The present embodiment of the invention 15 which we have described in detail is given merely by way of example and will attain all the features of advantage enumerated as desirable in the statement of the invention and the above description, but it is desired to point out that the numerous changes in the 20 details of construction, and in the combination and arrangement of parts may be resorted to without departing from the spirit or scope of the invention as hereinafter claimed or sacrificing any of its advantages.

Having thus described our invention, 25 what we claim as new is:—

1. In combination, a shaft, a reel rotatable with the shaft, housings having bear-

ings for the shaft, collector rings on the sides 30 of the reel within the housings, brushes supported in the housings in engagement with the collector rings, each brush including a holder comprising a body having a recess 35 therein, a pin extending transversely of the recess, a spring engaged with said pin, and means for turning the pin for tensioning the spring against the brush.

2. In a reel structure, a shaft, a pair of 40 housings having bearings receiving the shaft, a reel on the shaft between the housings comprising a pair of insulating disks, bars carried between the disks about the shaft, means for fixing the reel to the shaft, a collector ring on the outside of each disk, a bolt connected to the ring and extending 45 through the adjacent disk, a brush in each housing, means for supporting the brush in each housing and insulating it therefrom, a clamp on the exterior of each housing, wires supported on said clamps and connected to 50 the brushes within the housings.

In testimony whereof we affix our signatures.

BAILEY G. BIRD.
HENRY D. WRIGHT.
